UNITED STATES PATENT OFFICE.

WALTHER VOITH, OF ST. POELTEN, AUSTRIA, ASSIGNOR TO AMERICAN VOITH CONTACT COMPANY, INC., OF NEW YORK, N. Y., A CORPORATION OF NEW YORK.

FOURDRINIER MACHINE.

Application filed September 14, 1922. Serial No. 588,187.

To all whom it may concern:

Be it known that I, WALTHER VOITH, a citizen of the German Republic, residing at St. Poelten, Austria, and having a postal address at No. 280 Madison Avenue, New York city, New York, U. S. A., have invented new and useful Improvements in Fourdrinier Machines, of which the following is a specification.

10 My invention relates to Fourdrinier machines, and particularly to the feed of stock to the screen. The particular objects of my invention are to provide an improved feed device consisting of a high level stock gate 15 which allows of an even and perfect distribution of the stock to the screen, in combination with an improved distributor, by means of which a more even distribution of the fibres in the stock is attained.

20 In the accompanying drawings—

Fig. 1 is a broken front elevation of a stock vat in which my invention is embodied;

25 Fig. 2 is a section on the line 2—2, Fig. 1; and

Fig. 3 is a section on the line 3—3, Fig. 2, but drawn to a larger scale.

In order to obtain a paper product of good quality, it is necessary to insure the 30 uniform distribution of the wood fibres throughout the stock from which the sheet is made. Further it is necessary to insure the delivery of the stock from the vat to the screen in a sheet of uniform depth across the entire width of the screen. Finally it 35 is necessary to prevent any formation of knots, lumps and foam in the feed device.

The first two results are accomplished by a so-called high level stock vat of the type 40 indicated at 5 in Fig. 2, and already known in the prior art. To accomplish the third result, various devices have heretofore been provided for agitating the stock in the vat adjacent the delivery sluice, so that the fibres 45 in the stock will not gather into knots or bunches, which produce uneven spots in the final product. These stirrers or agitators have heretofore been constructed or operated in such manner that an objectionable 50 amount of foam is produced at the delivery sluiceway, and its presence is not only objectionable in the stock, but also results in the occurrence of irregularities in the stock sheet delivered to the screen.

55 In the construction here shown the stock

vat 5 is arranged adjacent the breast roll 6, around which the screen 7 travels. The stock 8 is delivered from the vat through the sluiceway 9 to the screen. At the intake from the vat to the sluice 9, I arrange 60 transversely of the vat, a perforated drum or roll 10 supported at one end by a hub 11 fast with the spindle 12, which passes through a stuffing box 13 in the side of the vat 5. At its outer end the spindle is fast 65 with a bevel gear 14 meshing with a similar gear 15 at the lower end of the spindle 16, driven through gears 17 and 18 from the shaft of belt wheel 19. At its opposite end the drum 10 is closed and supported in any 70 suitable way in the opposite side of the vat 5, for example, by a peripheral bearing ring 20. The perforations in the walls of the cylinder are of sufficient size to permit the free flow of the stock therethrough without 75 danger of choking. The speed of rotation of the drum may be varied, but is in any event such that little or no foam is created. The stock flows through the drum to the 80 sluice 9 with the pulp fibres thoroughly separated from each other and evenly distributed in the stock which is delivered to the sluice.

As is well known in the art, the stock 8 is delivered to the vat by an overflow weir 85 or similar arrangement. The incoming stock thus delivered creates a turbulent condition in the vat with wave-like agitation thereof which affects the delivery of the stock at the discharge opening to the screen, and 90 tends to cause ripples in the stock sheet which unfavorably affect the product, especially in a stock vat of the type shown in Fig. 2 where the speed of the stock flowing through the discharge opening or nozzle to the screen, has a high velocity. To meet this difficulty it has been heretofore proposed to provide weirs or overflow partitions in the vat which have the effect of forming a relatively quiet body of stock adjacent to the discharge opening. These arrangements are, however, objectionable for the reason, among others, that they cause a settling of the heavy components of the stock body, on the inlet side of the weirs or screens, thus necessitating further agitation of the mass in order to keep it uniform. By locating the cylinder 10 directly at the delivery opening 9, the turbulence of the stock in the vat is prevented from affecting the 100 105 110

flow at the discharge port, while the rotation of the cylinder distributes the fibres and secures a substantially uniform distribution thereof throughout the stock as it passes through the cylinder to the port 9.

In order to control the depth of the stock sheet delivered to the screen 7, I provide a gate in the form of an apron 21 hinged at 22, and working between the forwardly projecting cheeks 23 of the sluiceway. The apron 21 is of flexible material, such as sheet metal, and is bodily adjustable up and down to govern the delivery opening as a whole, while it is also adjustable at transversely spaced points by flexing the same, to insure perfect uniformity of thickness in the stock sheet across the entire width of the machine. Thus, links 24 are connected to the apron 21 at relatively closely spaced intervals. At their upper ends they are threaded at 25 and engaged by nuts 26 above and below the bosses 27 on the stirrups 28, by which the links are hung from eccentrics 29 on the transverse shaft 30. At one end the shaft is provided with a worm wheel 31 meshing with a worm 32 supported in the bracket 33 and operated by a hand wheel 34. The rotation of the shaft 30 and the cams 29 by means of the hand wheel 34, raises and lowers the several adjusting links 24 simultaneously and to an equal degree, thus increasing or decreasing the thickness of the stock sheet on the screen across the entire width of the latter. By manipulation of the hand nuts 26, at the head of any of the links 24, the apron 21 may be flexed at the area to which the particular link is attached. It is thus possible to vary the thickness of the stock sheet at any point transversely thereof by manipulation of the hand nuts 26.

Various modifications in details of construction and arrangement will readily occur to those dealing with the problem, without departing from what I claim as my invention.

I claim—

1. In a paper making machine, a travelling screen, a high level stock vat discharging thereto, an adjustable and flexible gate for regulating the depth of the stock sheet delivered to the screen from the vat, and means located adjacent to the discharge opening of the vat for substantially eliminating vat disturbance of the stock at the

discharge port and for insuring the delivery of the stock in substantially uniform condition to said port.

2. In a paper making machine, a travelling screen, a high level stock vat discharging thereto, an adjustable and flexible gate for regulating the depth of the stock sheet delivered to the screen from the vat, and a rotary cylindrical drum extending transversely of the vat and located adjacent to the discharge opening of the vat for substantially eliminating vat disturbance of the stock at the discharge port and for insuring the delivery of the stock in substantially uniform condition to said port.

3. In a paper making machine, a travelling screen, a high level stock vat discharging thereto, an adjustable and flexible gate for regulating the depth of the stock sheet delivered to the screen from the vat, and a rotary perforated cylindrical drum extending transversely of the vat and located adjacent to the discharge opening of the vat for substantially eliminating vat disturbance of the stock at the discharge port and for insuring the delivery of the stock in substantially uniform condition to said port.

4. In a paper making machine, a travelling screen, a high level stock vat discharging thereto, an adjustable and flexible gate for regulating the depth of the stock sheet delivered to the screen from the vat, and a rotary perforated cylindrical drum extending transversely of the vat and located adjacent to the discharge opening of the vat for substantially eliminating vat disturbance of the stock at the discharge port and for insuring the delivery of the stock in substantially uniform condition to said port, together with means for varying the speed of rotation of the drum.

5. In a paper making machine, the combination of a travelling screen, a high level stock vat discharging thereto, an adjustable and flexible gate for regulating the depth of the stock sheet delivered to the screen from the vat, a rotary perforated cylindrical drum extending transversely of the vat and located adjacent to the discharge opening of the vat, and means for varying the speed of the rotation of the drum.

In testimony whereof I have signed my name to this specification.

WALTHER VOITH.
